CLAIM

The ornamental design for a bushing, as shown and described.

DESCRIPTION

The bushing is used for connecting a cylindrical roll screen to a bracket that is used within a window or door frame. FIG. 1 is a top perspective view of the bushing embodying the design.

FIG. 2 is a bottom perspective view of the bushing embodying the design.

FIG. 3 is a side elevational view of the bushing embodying the design.

FIG. 4 is a top view of the bushing embodying the design.

FIG. 5 is a bottom view of the bushing embodying the design; and,

FIG. 6 is a cross-sectional view of the bushing embodying the design.
